PRODUCTION OF POWDERED CAPILLARY-ACTIVE SULFURIC ACID DERIVATIVES

Hendrik F. Dammers, Amsterdam, Netherlands, assignor to Shell Development Company, San Francisco, Calif., a corporation of Delaware

No Drawing. Application March 15, 1948, Serial No. 15,055. In the Netherlands March 21, 1947

4 Claims. (Cl. 241—3)

1

This invention relates to the manufacture of salts of organic acids having a $-\text{SO}_3\text{H}$ group in the molecule which are surface-active agents suitable for use in wetting, washing and emulsifying operations. It deals particularly with an improved method of producing compositions containing such salts in the form of substantially dry, non-coherent powders of relatively uniform, fine particle size.

The great bulk of synthetic detergents now on the market are salts of organic acids having a $-\text{SO}_3\text{H}$ group which is directly linked to a carbon atom of a hydrophobic group as in the sulfonic acids or is attached to an oxygen atom which is directly linked to a carbon atom of a hydrophobic group as in the sulfuric acid esters. Examples of a number of different salts of this type, which can be used in the process of the invention and which will be referred to generically hereinafter as sulfonic salts, are given in the November 1947 issue of "Chemical Industries," pages 811 to 824.

A common characteristic of these sulfonate salts as normally produced is that they yield particles having a marked tendency to stick together or agglomerate. This is undesirable, not only because it exerts an unfavorable influence on the appearance of the product since the agglomerated powder is darker in color, but also because the agglomeration interferes with accurate dosage of the detergent in use and decreases its rate of solution in solvents. Furthermore, apart from the foregoing disadvantages, consumers prefer products which are of the so-called "free-flowing" type.

The tendency of the dry pulverized sulfonate salts to agglomerate varies according to the nature and generally also the concentration of the sulfonic acid and/or sulfuric acid ester salt in the powder. The salts of the acid sulfuric acid esters produced by sulfating olefins of 8 to about 20 carbon atoms display this undesirable tendency in a particularly high degree. The tendency of the powders to stick together is generally less in the case of mixtures of the sulfonate salts with substantial amounts of inorganic salt, for example, 40% or more by weight, but even with such mixtures the agglomerating tendency is still substantial and quite undesirable. In fact, it is generally impossible to produce properly non-coherent powders having a high enough content of sulfonate salt to be a practically effective detergent or wetting or emulsifying agent by mixing the pulverized sulfonate salts with inorganic salts.

Now, according to the invention, it has sur-

2

prisingly been found that fine pulverized non-coherent powders having excellent detergent, wetting, emulsifying and foaming properties can be obtained—starting from dry or substantially dry sulfonic acid or acid sulfuric acid ester salts, or mixtures containing these sulfonate salts, which sulfonate salts or sulfonate salt-containing mixtures display a tendency to agglomerate when in powdered form—by grinding the sulfonate salt or sulfonate salt-containing mixture with an added finely divided powder which has little or no tendency to stick together.

As addition agents which may be added during grinding of the sulfonate salt according to the process of the invention, any substance solid at normal temperature, and which may be divided into a fine powder which shows little or no tendency to agglomerate, may be considered. These addition agents will be referred to generically hereinafter as non-agglomerating powders. As such, water-soluble inorganic salts such as alkali metal or ammonium sulfates, phosphates or chlorides have special advantages, and of these the neutral salts are preferred. However, if desired, one may also use for this purpose substances which are insoluble in water, such as talc or kaolin, or which are expansible with water without dissolving in it, such as bentonite or other colloidal clays; naturally, such substances can only be used when it is not objectionable that the products obtained do not completely dissolve in water. The substances to be added are preferably applied as a fine dry powder, preferably of about 100 to about 300 mesh.

The effect attained in the process according to the invention, viz. that, by grinding the initial material with the substance added to it, the tendency of the said material to stick together is eliminated—an effect which is not attained by simply mixing the substances—is probably due to the fact that the fracture surfaces formed in the grinding process are covered substantially as fast as formed with particles of the non-agglomerating powder added, and this prevents the particles of sulfonate salt formed during the grinding from combining again to form large conglomerates and forming a coarse product, generally of a yellowish color.

The quantity of the added substance with which the sulfonate salt is to be ground in order to attain the effect aimed at may vary within wide limits, according to the nature and the composition of the sulfonate salt and the nature of the non-agglomerating powder added thereto.

55 The degree of fineness to which the sulfonate

salt is ground also affects the quantity of non-agglomerating powder to be added; the finer the sulfonate salt is ground, the larger in general is the quantity of a given powder that has to be added in order to attain the desired effect. The quantities to be added, which may be ascertained experimentally for each case, usually amount to at least 25% by weight, calculated on sulfonate salt present, and are generally in excess of this figure. Thus, dry products with a content of about 60% secondary sulfuric acid ester salts may be ground with a quantity of sodium sulfate exceeding 100% (calculated on ester salt) to produce a mixture which does not display any tendency to stick together. In general, however, additions in consequence of which the content of sulfonate salt in the final product falls below about 25% cannot be used.

It has been found that in most cases, when sodium sulfate is used as the substance with which the capillary-active material is ground, very favorable results are obtained. Anhydrous sodium sulfate in the form of a fine dry powder, as it may, for example, be obtained by atomization-drying of an aqueous sodium sulfate solution, has been found particularly suitable. This favorable effect is connected with the low apparent specific weight of the sodium sulfate powder produced in this manner, as a result of which it will be easier to attain a homogenous division with this material in the grinding chamber. In view of this, it is in general particularly advisable to use non-agglomerating powders with a low apparent specific weight, i. e. from 0.1 to 0.5.

It may, however, be desirable in some cases, as previously pointed out, to use non-agglomerating powders such as talc or bentonite in place of or in addition to sodium sulfate, since talc, bentonite and the like, which have an even lower tendency to agglomerate than sodium sulfate, are more effective, on an equal weight basis, in preventing the agglomeration of sulfonate salts according to the invention.

The process according to the invention may be applied to sulfonate salts which have been brought into dry or substantially dry condition in any suitable manner. It is, however, of particular advantage in the improvement of sulfonate salts obtained by means of the known atomization-drying, followed by compression for raising the apparent specific weight. The products obtained according to the atomization-drying method generally have a very low apparent specific weight, which is undesirable, since the large volume of these products involves high cost of transport. Such products may be converted in any convenient manner into pulverized products with a higher apparent specific weight by compression and subsequent grinding.

In the process according to the invention, the non-agglomerating powder, by means of which the tendency of the dry sulfonate salt to stick together is checked, should be added to the latter while it is being ground. If desired, however, a portion of this non-agglomerating powder may also be first mixed with the sulfonate salt, and the mixture be subsequently ground while adding the remainder. If the dry sulfonate salt taken as starting material is compressed and subsequently ground, the non-agglomerating powder may be added either partly before compression and for the rest during the grinding of the compressed product or exclusively during the grinding.

Mills particularly suitable for the grinding are

those of the cross-stroke or hammer-stroke type, which apparatus renders it possible to prevent undesirable rises in temperature during the grinding.

While the process of the invention is, as previously pointed out, of special importance in its application to secondary sulfate acid ester salts derived from higher alkenes because of the greater agglomerating tendency of this type of sulfonate salt, the process may also be applied successfully and with advantage to the production of non-coherent powders of other sulfonate salts such, for instance, as primary sulfuric acid ester salts obtained by sulfating higher alcohols—which may, for example, have been produced by hydrogenation of fatty acids or by oxosynthesis—followed by neutralization, or alkyl sulfonic acid salts of eight or more carbon atoms per molecule which may be produced, for example, as described in U. S. Patent 2,276,090 or in other suitable ways, or soluble salts of alkylated aromatic sulfonic acids of the benzene series such as described in U. S. Patent 2,283,199, or sulfo-succinic acid ester salts and the like.

The process according to the invention is further illustrated with reference to the following examples:

Example I

By atomization-drying of an aqueous secondary sodium alkyl sulfate solution (obtained by reaction of a C₁₀—C₁₆ alkene fraction with concentrated sulfuric acid and neutralization of the reaction product with sodium hydroxide), a dry powder was produced, which contained 60% ester salt and 40% sodium sulfate.

This powder, which had an apparent specific weight of 0.1 to 0.2, was converted by compression into a product with a specific weight of 1.2 to 1.3.

The compressed product was then ground in a cross-stroke mill and subsequently mixed with about 70% by weight sodium sulfate produced by atomization-drying (apparent specific weight 0.3). The product thus obtained, which had an ester salt content of 35%, gave rise to a coarse-grained, light yellow powder, which showed a strong tendency to stick together and which, on being sifted on a sieve with 30 meshes to an inch, left behind a residue of 20%.

If, on the other hand, an equal quantity of sodium sulfate was added to the compressed product already during the grinding, a fine powder was obtained, of lighter color than the preceding product, which showed no tendency to conglomerate, and on being sifted on a sieve with 30 meshes to an inch yielded a residue of only 6%.

Example II

A capillary-active product consisting of about 98% of the sodium salt of sulfo-succinic acid di-octyl ester, which formed highly conglomerating grains, on being ground in a cross-stroke mill yielded a perfectly conglomerated mass, not an atom of which passed through a sieve with 30 meshes to an inch. Mixing of the product with bentonite or talc produced hardly any improvement.

By grinding the sodium sulfo-succinic acid di-octyl ester while adding 25% by weight bentonite, a fine product was obtained which, on being sifted on a sieve with 30 meshes to an inch, left no residue, and 25% residue on a sieve with 60 meshes to an inch.

Even finer pulverized products were obtained by grinding while adding 25% by weight and

65% by weight talc, respectively. On being sifted on a sieve with 60 meshes to an inch, these products left a residue of only 20% and 13%, respectively.

I claim as my invention:

1. In a process for producing a fine, non-coherent powder of relatively high apparent specific weight from a surface-active salt of an organic acid having a $-\text{SO}_3\text{H}$ group, the steps comprising (1) spray-drying an aqueous solution of said salt to produce a dry powder of relatively low apparent specific weight, (2) compressing the spray-dried powder into an agglomerate of relatively high apparent specific weight, (3) adding to the compressed agglomerate a dry powder of the type which retains its powder condition during a grinding operation, and (4) grinding the mixture of agglomerate and added powder to produce a powder of relatively high apparent specific weight; the amount of said dry powder added in step 3 being equal to at least 20% by weight of said salt but insufficient to reduce the concentration of said salt in the product to below 25%.

2. A process in accordance with claim 1 where-
in the surface-active salt is a water-soluble salt
of an alkyl sulfuric acid having 8 to 20 carbon
atoms per molecule.

3. A process in accordance with claim 1 where-
in the surface-active salt is a water-soluble salt
of an alkylated aromatic sulfonic acid of the
benzene series.

4. A process in accordance with claim 1 where-
in the dry powder is added to the agglomerated
surface-active salt at least in part during the
said grinding step, said powder being of about
100 to about 300 mesh and having an apparent
specific weight of about 0.1 to about 0.5.
